UNITED STATES PATENT OFFICE.

FRED DORNBUSCH, OF OTTAWA, ILLINOIS.

PORTABLE WOODWORKING MACHINE.

Application filed August 20, 1923. Serial No. 658,224.

To all whom it may concern:

Be it known that I, FRED DORNBUSCH, a citizen of the United States, residing at Ottawa, in the county of La Salle and State 5 of Illinois, have invented a new and useful Improvement in Portable Woodworking Machines, of which the following is a specification.

It is an object of my invention to provide 10 a new and improved portable wood-working machine which can be readily moved from place to place for use in the field or on the job, of simple, durable, efficient and inexpensive construction. It is a further object 15 to provide a machine of this type which may be readily and quickly adjusted and applied to tables or benches of various heights or thickness.

The above and other features of novelty, 20 advantages and capabilities will become apparent from a detailed description of the accompanying drawings in which I have illustrated one form of my invention, but the construction there shown will be understood 25 as illustrative only and not as defining the limits of my invention.

Fig. 1 is a side elevational view of a portable wood-working machine embodying one form of my invention.

30 Fig. 2 is an elevational view of the cutting blades mounted in place.

Fig. 3 is a top plan view of the same, and

Fig. 4 is a side elevational view of one of the tongue and groove blades.

35 Referring to the drawings in detail, the machine as illustrated consists of a base 10, integrally provided with a horizontal bearing 11, in which is rotatably mounted a shaft 12, which shaft in turn, is by means of a flexible coupling 13, connected to a suitable motor (not shown). The shaft 12, has fastened to its inner end by any suitable means, a beveled gear 14. The base 10, is integrally provided with an arm or extension 15 having a suitable vertical bearing or opening in which is rotatably mounted a shaft 16, having non-rotatably mounted on its lower end a beveled gear 17 designed to mesh with the beveled gear 14. The shaft 16 extends 40 upwardly through the table or support 18 and has non-rotatably mounted on its upper end a head 19. Mounted on the bearing extension 15^a, of the arm 15 is a collar 20, which collar is integrally provided with a

plate 21. The plate 21 is adapted to be secured to the work bench or table support 18, by means of suitable screws as shown. In order to accommodate the machines to tables of different heights or supporting boards of different thickness the collar 20 55 may be vertically adjusted on the extension 19 by means of the set screws 22.

By providing the collar 20 with the integral plate 21, the table can be readily lined up with the cutting tool or rather the cutting tool with the table. Adjustably mounted on opposite sides of the head 19 are suitable cutting tools or blades.

In Fig. 1 and 2 there is shown applied to the head, blades 23 for cutting quarter 70 round molding, while in Fig. 4 there is shown blades 24 for cutting a tongue and groove. In both cases the blades are provided with suitable slots through which pass suitable set screws 25 so that the blades 75 may be readily and quickly adjusted as described.

From the foregoing description it will be apparent that I have provided a machine which possesses to the fullest extent the 80 features heretofore pointed out as well as many other inherent advantages.

Having thus described my invention, I claim:

In a light portable wood-working machine, the combination of a base having an upwardly extending arm provided with a horizontal bearing, and a vertical arm provided with a vertical bearing, all formed integrally with the base, a driving shaft 85 mounted in the horizontal bearing, a driven shaft mounted in the vertical bearing, an adjustable collar mounted on the vertical bearing and provided with a horizontal plate 90 adapted to be secured to a bench or support, 95 a blade-head non-rotatably mounted on the upper end of the driven shaft, cutting blades mounted on said head and means for adjusting said blades substantially as and for the purpose set forth.

In witness whereof, I have hereunto subscribed my name to this specification in the presence of witnesses.

FRED DORNBUSCH.

Witnesses:

CHARLES COSTELLO,
JOHN W. McCauslin.
